UNITED STATES PATENT OFFICE.

OLIVER N. MILLER, OF FLORENCEVILLE, NEW BRUNSWICK, CANADA, AS
SIGNOR OF ONE-HALF TO G. FRED TURNER, OF FLORENCEVILLE, NEW
BRUNSWICK, CANADA.

CHIMNEY-CLEANER.

No. 854,101.

Specification of Letters Patent.

Patented May 21, 1907.

Application filed April 3, 1905. Serial No. 253,718.

To all whom it may concern:

Be it known that I, OLIVER NELSON MILLER, a subject of the King of England, residing at Florenceville, in the county of Carleton, Province of New Brunswick, Canada, have invented certain new and useful Improvements in Chimney Clean-Outs; and I do hereby declare that the following is a full, clear, and exact description of the invention, such as will enable others skilled in the art to which it appertains to make and use the same.

My invention relates to chimney cleaning apparatus; the object of my invention is to provide a safe, efficient and durable clean out for a chimney, which may be operated either from the bottom or the top of the chimney; and my invention consists of the construction, combination and arrangement of parts as herein illustrated and described.

In the accompanying drawings, forming a part of this application, in which drawings similar reference characters designate corresponding parts, I have illustrated one form of embodiment of my invention; and in which drawings:

Figure 1 is a central vertical section of a chimney, showing the application of my invention; Fig. 2 is a horizontal section, taken approximately on the line 2—2 of Fig. 1; and Fig. 3 is a perspective view of one of the scraping members used in my invention and herein described.

Referring to the drawings, 4 designates the chimney, which is usually of square shape. Disposed in the upper portion of the chimney is a cross-piece 5, which may be attached in any suitable manner, as by laying it across the opening in the upper end of the chimney. Disposed on the cross-piece 5 is a pulley 6, through which is run a chain, which extends down through the chimney over one side of a double pulley 8, which latter pulley is pivotally secured to the chimney, as by the eye 9.

Attached to the upper end of the chain 7 is a link 10, which is also attached to the upper end of a bar 11, provided at its opposite ends with screw-threads. At both ends the bar 11 is provided with a collar 12, which collar is maintained on the bar as by the nuts 13, one nut being disposed on each side of each collar.

Connecting the collars 12 is a plurality of members 14, preferably formed of heavy wire

having a certain amount of spring, to accentuate which spring the said members 14 are provided with the loops 15, each being provided with two loops.

The lower end of the bar 11 is provided with a link 16, to which link is secured a chain 17, running over the side of the double snatch-block 8 opposite to the chain 7, so that the lower ends of this chain may be joined together if desired.

It is obvious from the foregoing description that the bar 11, with the parts connected thereto, may be reciprocated from top to bottom and from bottom to top of the chimney, by an operator stationed at either end of the chimney.

In order to effectively scrape the interior of the chimney, I provide for each side thereof a pair of telescoping scrapers 18, preferably having an angular body portion 18^a and outwardly flaring flanges 18^b, which are provided in their arches with slots 19. These members are slidably connected together by the rods 20, by bending the ends of said rods into the eyes 21. The rods are connected to the spring members 14 by the eyes 22 formed on said members, which latter eyes work into the slots 23 also formed in the arches of said members 18. By this construction, the members 18 being connected at their ends to the members 14, it will be evident that the members 18 will be normally held in their most distended position. But when inserted in a flue or chimney of less dimensions than their greatest length they will readily telescope into a smaller space. By reciprocating the parts through a chimney or flue, as described all the soot will be readily removed. It will also be understood that for chimneys and flues of a shape other than square the only change necessary in my invention is to substitute scrapers of a different shape, to conform to the contour of the flue or chimney to be cleaned.

Having thus fully described my invention, what I claim as new and desire to secure by Letters Patent is:

1. A chimney clean out comprising a plurality of cleaners having angular bodies and flaring flanges said bodies having a plurality of slots therein and being arranged in pairs, rods arranged on opposite sides of each pair and each having an eye on one end extending

through a slot and connected to the other rod, springs provided with, eyes adapted to engage said rods through some of said slots, and means connected with said springs for reciprocating said cleaners through a chimney.

2. A chimney clean out comprising a bar provided with oppositely screw-threaded ends, collars disposed on the opposite ends of the bar, nuts disposed on the screw-threaded ends of the bar on each side of said collars, springs secured at their opposite ends to the

collars and provided intermediate of their ends with loops and eyes, cleaners arranged in telescoping pairs and secured to said eyes, and means for reciprocating said structure through a chimney. 15

In witness whereof I have hereunto set my hand in the presence of two witnesses,

OLIVER N. MILLER.
